UNITED STATES PATENT OFFICE.

GEORGE H. HESS, OF LA GRANGE PARK, ILLINOIS.

APPARATUS FOR DRYING AND COOLING SUBSTANCES.

1,151,268.

Specification of Letters Patent. Patented Aug. 24, 1915.

Application filed January 15, 1915. Serial No. 2,355.

To all whom it may concern:

Be it known that I, GEORGE H. HESS, a citizen of the United States, residing at La Grange Park, in the county of Cook and State of Illinois, have invented a new and useful Improvement in Apparatus for Drying and Cooling Substances, of which the following is a specification.

My invention relates to the drying and 10 cooling of substances in general required to be dried, but more particularly to grain, seeds and the like substances.

In the operating of cooling and drying apparatus in general, it is customary to introduce the substance to be dried into the drying racks, and after subjecting it for the requisite length of time to the drying currents of air, to discharge it into the cooling racks, and thereupon refill the drying racks 20 with a new charge to be dried. Racks of this character, as usually constructed, are of relatively large capacity, and as the quantities of substances to be dried vary, it often occurs that the last charge introduced into the drying racks is insufficient to fill the same, with the result of causing the upper portions of the racks to present relatively free passage for the drying air, which prevents the proper subjection of the substance in the bottom portions of the drying racks, to the air, with the manifest disadvantages. Furthermore, it is desirable, in order that economy in the operation of the apparatus be effected and the length of time 30 required for the drying operation be reduced, that the apparatus be of such construction that the material to be dried may be subjected to different degrees of heated air in stages, in the first stage of the drying

40 operation, to a relatively high temperature, which the material, such as grain, may be subjected to in this stage of the drying operation, without damaging the grain owing to its relatively wet condition, and at the 45 following stage to a less temperature.

My primary objects are to provide improvements in apparatus of the character referred to, whereby the above-stated objections are avoided; to provide a construction of apparatus whereby the material to be dried may, during the drying operation, be subjected to air of different degrees of temperature, successively; and generally to

improve apparatus of the type above-referred to to the end that they shall operate 55 the better to perform the work required.

Referring to the accompanying drawings—Figure 1 is a sectional view in side elevation of a drying and cooling apparatus constructed in accordance with my invention, one side of the housing being removed, the section being taken at the line 1 on Fig. 2 and viewed in the direction of the arrow. Fig. 2 is a sectional elevational view taken at the line 2 on Fig. 1 and viewed 60 in the direction of the arrow. Fig. 3 is a section taken at the line 3 on Fig. 1 and viewed 65 in the direction of the arrow. Figs. 4, 5 and 6 are sections taken at the lines 4, 5 and 6, respectively, on Fig. 1 and viewed 70 in the directions of the respective arrows. Fig. 7 is an enlarged section taken at the line 7 on Fig. 5 and viewed in the direction of the arrow; and Figs. 8 and 9, sections taken at the lines 8 and 9, respectively, 75 on Figs. 7 and 8 and viewed in the directions of the respective arrows.

In the particular construction illustrated, the racks for the material to be dried and cooled are shown as housed in a building 80 10 and are formed of series of upright plates 11 spaced apart with louvered angle-shaped plates 12 connecting the plates 11 together and inclining at their lower ends inwardly in staggered relation, as represented particularly in Fig. 7, the plates 12, by reason of their arrangement as illustrated serving to permit the passage of air through the racks from one side to the other, and consequently through the substances 90 located in the racks, as hereinafter described.

The racks thus provided are uprightly disposed and are spaced from each other horizontally, as represented in Figs. 4, 5 and 95 6, in the arrangement illustrated, wherein four racks are shown, five spaces being thus provided which are divided horizontally by partitions 13 and 14, the partitions 13 being about midway between the bottoms and tops 100 of the racks and the partitions 14 about midway between the partitions 13 and the tops of the racks, the partitions 13 and 14 dividing the spaces between the racks hereinbefore referred to, into chambers 15 to 29 105 inclusive.

The interior of the racks communicate at their upper ends with garners 30 for receiving the substance to be dried or otherwise treated to air currents, and at their lower ends open into a receiving hopper 31, it being understood that the passages afforded by the racks for the substance to be dried extend continuously from top to bottom of the apparatus. At intervals the racks contain valves 32 for controlling the flow of the material in the racks, valve mechanism for this purpose being located at a point immediately below the plane occupied by the partitions 13, and also at the bottom of the racks and intermediate these two positions, thus making three sets of valve mechanisms in the lower cooling portion of the apparatus. These valve mechanisms may be of any suitable construction; those illustrated comprising inclined slide-valves 32 which are slidably confined at their ends on guides 32^a on the plates 11 and are adapted to be reciprocated into and out of position for closing the racks to the passage of the material therethrough. These slide-valves are actuated by shafts 33 having cranks 34 pivotally connected at 34^a to links 35, the latter in turn being pivotally connected at 35^a with the slide-valves 32, whereby, when the shafts 33 are rotated the slide-valves controlled thereby are moved into or out of position for obstructing the passage of the material through the racks, depending on the direction in which the shafts 33 are rotated, the horizontal series of valves being spaced apart vertically the same distance, and a distance substantially equal to the height of the chambers 25 to 29 inclusive, these three sets of valve mechanisms being independently operable through the medium of actuating means represented at 36 and serving, when projected across the racks, to arrest the flow therethrough of the material above the valves.

The passages 15, 17 and 19 are closed at the left hand end of the apparatus and the passages 16 and 18 are closed at the right hand end thereof by plates represented at 37 and 38 respectively, the passages 16 and 18 opening into a chamber 39 formed in the housing 10 and open to the atmosphere through a window 40 in the housing, and to the space below the grating 39^a; and the passages 15, 17 and 19, which form exhaust passages, opening at the other end of the apparatus into a chamber 41 in the housing. The chamber 41 contains a blower 42 of any suitable construction and operated in any desirable manner, the inlet to which, represented at 43, communicates with the interior of the chamber 41, whereby when the blower 42 is actuated, cool air is drawn through the window 40 or grating 39^a into the chamber 39, thence into the passages 16 and 18 and through the material in the

racks, which is thereby cooled, thence into the passages 15, 17 and 19, and into the blower.

The outlet of the blower 42 communicates with a conduit 44 which opens into a heating chamber 45 divided horizontally into upper and lower sections, each containing a heating coil 46, by a partition 47 located in the same plane as the partitions 14, the partition 47, however, reaching short of the end wall of the chamber 45, as represented in Fig. 1, to form a passage 48 between the upper and lower sections of the chamber 45, said passage being controlled by a damper 49 mounted on a shaft 50 journaled in the wall of the housing, for a purpose hereinafter explained, the shaft 50 being provided with means (not shown) for operating it to open and close the passage 48.

The passages 20, 22 and 24 are closed at the left hand end of the apparatus by plates 51 and the passages 21 and 23 are closed at the right hand end thereof by plates 52, thus leaving the right hand end of the passages 20, 22 and 24 in open communication with the interior of the lower section of the heating chamber 45 and the ends of the passages 21 and 23 at the left hand end of the apparatus open to a chamber 53 which may communicate, as shown, with the atmosphere exterior of the housing 10. The passages, 25, 27 and 29 are closed, at the right hand end of the apparatus, to the interior of the heating chamber 45, by means of plates 54; and the passages 26 and 28 are closed to the chamber 53 at the other end of the apparatus by plates 55, the passages 26 and 28 thus opening at the right hand end of the apparatus into the upper section of the heating chamber 45 and the passages 25, 27 and 29 opening at the other end of the apparatus into the chamber 53.

It will be understood from the foregoing that heated air forced into the chamber 45, assuming the passage 48 to be open, passes through both of the heating coils 46, thus raising the temperature of the air discharged by the blower 42 through the conduit 44. The air in the lower section of the chamber 45 discharges into the passages 20, 22 and 24, thence passes through the open sides of the racks and the substances therein, and discharges into the passages 21 and 23, and thence into the exhaust chamber 53. The air in the upper section of the chamber 45 discharges into the two passages 26 and 28, thence passes through the racks and the substances therein and discharges into the passages 25, 27 and 29, from which it escapes into the exhaust chamber 53.

It will be noted that in accordance with the preferred arrangement illustrated, the drying air discharged into the racks from the lower section of the heating chamber passes in one direction through the racks, as

indicated by the arrows in Fig. 5, and that the air discharged into the upper portions of the racks from the upper section of the heating chamber 45, passes through these 5 racks in the contrary direction, as shown by the arrows in Fig. 4, and thus the substances being dried in the drying portions of the racks, namely, those portions which are located above the partitions 13, is subjected to 10 heated air passed therethrough it contrary direction, which serves very effectually to perform the drying function, as more specially hereinafter set forth.

In the preferred operation of the apparatus, the material to be dried is introduced 15 into the garners, the uppermost set of valves 32 being closed, to fill the racks above the last-referred-to valves. The damper 49 is then closed and the blower started into 20 operation which causes heated air to be forced through the material in the lower section of the drying rack. This operation would continue preferably for a length of time substantially equal to one-half of the 25 length of time the material is to be subjected in the drying operation, whereupon the damper 49 would be opened causing heated air to pass into both of the sections of the drying racks, this operation continuing until 30 the material in the lower section of the drying rack has become sufficiently dry, whereupon the upper set of valves 32 are opened permitting the material which was in the lower section of the drying rack to 35 descend into the upper section of the cooling rack wherein it is sustained by the middle set of valves 32. The material which was in the upper section of the drying racks and which, by the above described drying operation, 40 has been subjected to the drying heat for about one-half the desired length of time, thus descends into the lower section of the drying rack and fresh material to be dried descends from the garner into the upper section of the drying racks. The damper 45 49 remaining open, heated air continues to pass through both the upper and lower sections of the drying racks and when the material in the lower section of the drying rack has been subjected to heated air for a sufficient length of time to dry the material, the operator closes the upper set of valves 32 and opens the intermediate set of these 50 valves, having first closed the lowermost set of valves 32. Thus, the material which was delivered into the upper portion of the cooling rack and was cooled therein by currents of cold air drawn in from the window 40 by the fan 42 and passing through the racks, 55 is caused to descend into the lower portion of the cooling racks to be subjected to further cooling. The intermediate set of valves 32 are then closed and the uppermost set of valves 32 opened to permit the dried material in the lower section of the drying racks

to descend into the upper portion of the cooling racks and be replaced by the material in the upper section of the drying racks, the latter being, in turn, replaced by fresh material from the garners. It will thus be 70 understood that the preferred operation of the apparatus is to cause a charge of material to be subjected to the drying and cooling operations in stages, the material being advanced intermittently through the apparatus, it being understood that the lowermost set of valves 32 control the discharge of the dried and cooled material from the racks, the intermediate set of valves 32 being closed in this discharge operation. 80

There are certain advantages in performing the drying operation in separate stages, as hereinbefore explained, especially under certain conditions. Certain of the chief advantages are that it permits of the subjection 85 of the material, at different stages in the drying operation, to different degrees of heat which may be accomplished by supplying greater heat to one or the other of the coils 46, which latter, in practice, would be connected 90 up with a source of heat medium in such way, as will be manifest, as to permit them to be independently heated and to different temperatures, if desired, this being desirable, more particularly for economical reasons, as 95 the material usually operated on in driers of this general type is of such character that it may be subjected to relatively greater heat when in wet or damp condition than after it has become partly dried. Furthermore, this 100 feature of the construction permits of the passage of the drying air through the racks in one direction in one section thereof in the opposite direction, and through the racks in the other section thereof, and produces 105 agitation of the material in its movement from one section of the drying rack to the other section, these conditions being favorable to the effective drying of the material 110 expeditiously.

Another advantage arising from the feature of providing a drying section formed of upper and lower sections is presented in the treatment of the material at the end of a run. Should the mass of material to be 115 dried be of such volume that the last charge introduced into the drying portions of the racks is sufficient only to substantially half fill these portions of the racks, the operator will close the damper 49, thus causing all of 120 the heated air to discharge into the lower section of the heating chamber 45, and thus all of the heated air will pass through the racks containing the material to be dried, which effectually dries the charge, even 125 though it be of a volume less than that requisite to completely fill the drying portions of the racks.

While I have illustrated and described a particular construction of apparatus, I do 130

not wish to be understood as intending to limit my invention to its embodiment in this particular construction, as the same may be variously modified and altered without departing from the spirit of my invention.

What I claim as new and desire to secure by Letters Patent, is:—

1. In apparatus of the character set forth, the combination of drying racks and means for causing heated air to pass into one portion of said racks through one side thereof and into another portion thereof through the opposite side thereof.
2. In apparatus of the character set forth, the combination of drying racks, and means for causing separate bodies of heated air to pass into different portions of said racks through opposite sides thereof, respectively.
3. In apparatus of the character set forth, the combination of drying racks, conduits arranged to conduct heated air through one portion of said racks in one direction and through another portion of said racks in the opposite direction, and means for supplying heated air to said conduits.
4. In apparatus of the character set forth, the combination of drying racks, a chamber having separate compartments for supplying heated air to the drying racks, means for causing the heated air to pass from one of said compartments through the lower portions of said racks in one direction, and means for causing the heated air to pass from the other of said compartments through the upper portions of said racks in the opposite direction.
5. In apparatus of the character set forth, the combination of drying racks, conduits arranged to conduct heated air through the lower portions of said racks in one direction and through the upper portions of said racks in the opposite direction, and means controlling the supply of air to said conduits constructed and arranged to cause air to pass through both of said portions of said racks or through one portion only thereof.
6. In apparatus of the character set forth, the combination of drying racks, conduits arranged to conduct heated air through the lower portions of said racks in one direction and through the upper portions of said racks in the opposite direction, and means for causing air of different temperatures to pass through said conduits, respectively.
7. In apparatus of the character set forth, the combination of drying racks, conduits arranged to conduct heated air through the lower portions of said racks in one direction and through the upper portions of said racks in the opposite direction, means for causing air of different temperatures to pass through said conduits, respectively, and means for controlling the passage of air through said conduits operative to permit

air to pass through both of said conduits, or 65 one only thereof.

8. In apparatus of the character set forth, the combination of drying racks, conduits arranged to cause heated air to pass through the lower portions of said racks in one direction and through the upper portions of said racks in the opposite direction, means whereby the air in one of said conduits will be caused to be at a higher temperature than in the other of said conduits, and means for 70 75 controlling the passage of air to cause it to pass through both of said conduits or one only of said conduits.

9. In apparatus of the character set forth, the combination of cooling racks and superposed drying racks, upper and lower valve mechanisms in said cooling racks, the upper valves controlling the outlet from said drying racks, the capacity of the cooling racks between said sets of valves being equal to a 80 portion only of the capacity of the drying racks, means dividing said drying racks into superposed sections each of a capacity substantially equal to the capacity of the cooling racks between said sets of valves, and 85 means for supplying heated air to the sections of said drying racks to pass therethrough, controllable for supplying air at one temperature to one of said sections of the drying rack and air at a different temperature to the other section of said drying 90 95 rack.

10. In apparatus of the character set forth, the combination of cooling racks and superposed drying racks, upper and lower 100 valve mechanisms in said cooling racks, the upper valves controlling the outlet from said drying racks, the capacity of the cooling racks between said sets of valves being equal to a portion only of the capacity of 105 the drying racks, means dividing said drying racks into superposed sections each of a capacity substantially equal to the capacity of the cooling racks between said sets of valves, and means for causing heated air to 110 pass through one portion of the racks in one direction and through another portion thereof in the opposite direction.

11. In apparatus of the character set forth, the combination of drying racks with 115 passages therebetween, partitions in said passages, certain of said passages being closed at one end above said partitions and closed at their opposite end below said partitions, and the other of said passages being 120 closed above and below said partitions adjacent the open ends of said first-referred to passages, and conduits arranged to supply heated air to the open ends of the racks at one end of the apparatus.

12. In apparatus of the character set forth, the combination of drying racks, separate compartments in communication with

each other for supplying heated air to different portions of said racks, a conduit for supplying air to the lower one of said compartments, and a valve controlling the opening between said compartments.

13. In apparatus of the character set forth, the combination of drying racks, separate compartments in communication with each other for supplying heated air to dif-

ferent portions of said racks, heating means 10 in said compartments, a conduit for supplying air to the lower one of said compartments, and a valve controlling the opening between said compartments.

GEORGE H. HESS.
